CLAIM

The ornamental design for a toy archery set, as shown and described.

DESCRIPTION

FIG. 1 is a front view of a first embodiment of a toy archery set showing my new design;

FIG. 2 is a right side view of the first embodiment thereof;

FIG. 3 is a left side view of the first embodiment thereof;

FIG. 4 is a back view of the first embodiment thereof;

FIG. 5 is a top view of the first embodiment thereof;

FIG. 6 is a bottom view of the first embodiment thereof;

FIG. 7 is a perspective view of another state of the first embodiment thereof;

FIG. 8 is a front view of a second embodiment of a toy archery set showing my new design;

FIG. 9 is a right side view of the second embodiment thereof;

FIG. 10 is a back view of the second embodiment thereof;

FIG. 11 is a left side view of the second embodiment thereof;

FIG. 12 is a top view of the second embodiment thereof;

FIG. 13 is a bottom view of the second embodiment thereof;

FIG. 14 is a perspective view of another state of the second embodiment thereof;

FIG. 15 is a front view of a third embodiment of a toy archery set showing my new design;

FIG. 16 is a right side view of the third embodiment thereof;

FIG. 17 is a left side view of the third embodiment thereof;

FIG. 18 is a back view of the third embodiment thereof;

FIG. 19 is a top view of the third embodiment thereof;

FIG. 20 is a bottom view of the third embodiment thereof;

FIG. 21 is a perspective view of another state of the third embodiment thereof;

FIG. 22 is a front view of a fourth embodiment of a toy archery set showing my new design;

FIG. 23 is a right side view of the fourth embodiment thereof;

FIG. 24 is a left side view of the fourth embodiment thereof;

FIG. 25 is a back view of the fourth embodiment thereof;

FIG. 26 is a top view of the fourth embodiment thereof;

FIG. 27 is a bottom view of the fourth embodiment thereof; and,

FIG. 28 is a perspective view of another state of the fourth embodiment thereof.
